US0D1002155S

(12) **United States Design Patent** (10) **Patent No.:** **US D1,002,155 S**
(45) **Date of Patent:** **** Oct. 24, 2023**

(54) **SHOE**

(71) Applicant: **Hero GmbH & Co. KG**, Mainburg (DE)

(72) Inventor: **Michael Haimerl**, Mainburg (DE)

(73) Assignee: **Hero GmbH & Co. KG**

(**) Term: **15 Years**

(21) Appl. No.: **29/855,291**

(22) Filed: **Sep. 30, 2022**

Assistant Examiner — Yelizaveta Y Masalimova

(74) Attorney, Agent, or Firm — AKERMAN LLP; Peter A. Chiabotti

(57) **CLAIM**

The ornamental design for a shoe, as shown and described.

DESCRIPTION

FIG. 1 is a perspective view of a shoe;

FIG. 2 is a top view thereof;

FIG. 3 is a bottom view thereof;

FIG. 4 is a right side view thereof;

FIG. 5 is a left side view thereof;

FIG. 6 is a front view thereof; and,

FIG. 7 is a back view thereof.

The broken lines represent portions of the shoe that form no part of the claimed design.

1 Claim, 7 Drawing Sheets
